UNITED STATES PATENT OFFICE.

VÁCLAV HEJMA, OF BRNO, CZECHOSLOVAKIA.

CUTTING DEVICE FOR REAPING, MOWING, AND LIKE MACHINES.

Application filed April 25, 1925, Serial No. 25,864, and in Czechoslovakia February 11, 1924.

The present invention relates to a cutting device for reaping, mowing and like machines of the kind that comprise a series of stationary finger pieces operating in conjunction with knives mounted on an endless chain.

The object of the invention is to improve upon this kind of device to provide for a better cutting effect and a more sturdy construction.

Referring to the accompanying drawings, Figure 1 is a plan view of the cutter with the upper rail or bar removed, Figure 2 a vertical longitudinal section on the line X—X Figure 3, and Figure 3 a vertical cross-section on the line Y—Y Figure 2.

In the drawings divided knives a are shown each with six teeth, which are provided at both ends with flat attachments a' , a^2 bent backwards in a horizontal direction through a longitudinal slot, into the interior of a casing running horizontally and transversely through the machine and formed of two U-shaped supporting arms b and c . On the lower support c there are mounted the usual finger pieces d .

The two supports b , c are provided internally with longitudinal grooves, in which an endless chain e is guided with its pins or pivots. The attachments a^2 of the divided knives are pivotally mounted on corresponding pins of the endless chain, whilst the attachments a' are provided with pins a^3 guided in the groove of the support c . The endless chain e is guided at both ends of the casing b , c over cog wheels or sprocket wheels rotatable round perpendicular axes, and through a second casing fashioned similar to the casing b , c , so that the knives a always rotate in one and the same direction. In this way a much larger cutting surface is obtained than with mowing machines the knives of which are moved to and fro. The pins a^3 , are identical in every respect with the pins on the attachment a^2 , the only difference being that the last mentioned pins have a double function, namely as the pivot of the endless chain and a support for one end of a knife section, while the pin a^3 , functions merely as the guiding element of the other end of the knife section.

Having now particularly described and ascertained the nature of my said invention and in what manner the same is to be performed, I declare that what I claim is:

55

1. A cutting device for reaping, mowing and like machines, comprising in combination a hollow casing having longitudinal grooves in opposed inner walls thereof, stationary finger pieces fastened to said casing, an endless chain traversing said casing, and having pins for slidably guiding the same in said grooves, and knife sections each articulated at one end to a pin of said endless chain and provided at the other end with a pin adapted to be guided in said grooves independently of said chain.

60

2. A cutting device for reaping, mowing and like machines, comprising in combination a hollow casing, longitudinal grooves formed in the top and bottom inner faces of the cavity in said casing, stationary finger pieces fastened to said casing, an endless chain arranged in said casing and having pins by means of which it is slidably guided in said grooves, and knife sections each articulated at one end to a pin of said endless chain and provided at the other end with a pin adapted to be guided in said grooves of said casing independently of said chain.

65

3. A cutting device for reaping, mowing and like machines, comprising in combination a hollow casing, longitudinal grooves formed in the top and bottom inner faces of the cavity in said casing, stationary finger pieces fastened to said casing, an endless chain arranged in said casing and having pins by means of which it is slidably guided in said grooves, and a plurality of integral knives forming knife sections each articulated at one end to a pin of said endless chain and provided at the other end with a pin adapted to be guided in said grooves of said casing independently of said chain.
